US0D1050856S

(12) **United States Design Patent** (10) **Patent No.:** **US D1,050,856 S**
(45) **Date of Patent:** **** Nov. 12, 2024**

(54) **MULTI-ACCESSORY MOUNT**

(71) Applicant: **GBRS Group LLC**, Virginia Beach, VA (US)

(72) Inventors: **Blair Cole Fackler**, Virginia Beach, VA (US); **Donald Wayne Shipley, III**, Virginia Beach, VA (US)

(73) Assignee: **GBRS Group LLC**, Virginia Beach, VA (US)

(**) Term: **15 Years**

(21) Appl. No.: **29/867,416**

(22) Filed: **Oct. 24, 2022**

(51) **LOC (14) Cl.** **08-08**

(52) **U.S. Cl.**

USPC **D8/349**; D22/108; D22/109; D22/110

(58) **Field of Classification Search**

USPC D8/349; D21/567, 572-575; D22/103,

D22/108, 109, 110, 199

CPC F41G 11/00; F41G 11/003; F41G 1/16;

F41A 35/00; F41C 27/00; F14G 11/004

(57) **CLAIM**

The ornamental design for a multi-accessory mount as shown and described.

DESCRIPTION

FIG. 1 is a left view of a multi-accessory mount according to the disclosure;

FIG. 2 is a right view thereof;

FIG. 3 is a front view thereof;

FIG. 4 is a rear view thereof;

FIG. 5 is a top view thereof;

FIG. 6 is a bottom view thereof;

FIG. 7 is a front perspective view thereof; and,

FIG. 8 is a rear perspective view thereof.

The evenly spaced broken depict portions of the multi-accessory mount that form no part of the claimed design. The dot-dash lines depict the bounds of the claim that form no part thereof.

1 Claim, 6 Drawing Sheets
